UNITED STATES PATENT OFFICE.

GEORGE EDWARD BLAKE AND CARROLL MELVIN BELL, OF GREENCASTLE, INDIANA.

PRESSURE-GENERATOR.

SPECIFICATION forming part of Letters Patent No. 727,067, dated May 5, 1903.

Application filed January 27, 1902. Serial No. 91,406. (No model.)

To all whom it may concern:

Be it known that we, GEORGE EDWARD BLAKE and CARROLL MELVIN BELL, citizens of the United States, residing at Greencastle 5 in the county of Putnam and State of Indiana, have invented a new and useful Pressure-Generator, of which the following is a specification.

The object of our invention is to provide an improved generator for producing a supply of fluid under high pressure.

A further object of the invention is to so construct a generator of this kind as to prevent the admixture of a fresh charge of explosive compound with gases already exploded 15 and under pressure.

A still further object is to provide for the removal of all of the exploded gases from a generator before a fresh charge is exploded.

A still further object is to provide a generator which will be wholly automatic in its 20 operation.

With these and other objects in view the invention consists in the novel construction and arrangement of parts hereinafter described, and illustrated in the accompanying drawings and pointed out in the appended claims.

In the drawings, Figure 1 is a sectional elevation of a pressure-generator constructed in 30 accordance with our invention, illustrating the position of the movable partition or piston when the generator is filled with exploded gas under pressure. Fig. 2 is a similar view illustrating the position of the movable partition or piston immediately after the explosion of a charge.

1 indicates a chamber, preferably cylindrical in form and having an upper head 2 and a lower head 3, the only outlet from the 40 chamber being through a pipe 4, which leads to an engine of any character or to other motor where the pressure is to be utilized. Fitting closely in the chamber is the vertically movable partition 5, which may be provided 45 with packing-rings, if necessary, there being an opening 6 extending through said partition to permit of the passage of gas when the partition is in the elevated position illustrated in Fig. 2. The opening 6 is normally closed 50 by a valve 7, carried by a valve-stem 8, adapt-

ed to a suitable guide or support, the valve being moved to the closed position (illustrated in Fig. 1) when the partition reaches the lower end of the chamber and being moved to the open position (illustrated in Fig. 2) when the 55 partition is at the top of the chamber. Connected to the lower head 3 is a mixing-chamber 9, into which extend a gas-pipe 10 and an air-pipe 11, the gas and air being forced from a tank or other source of supply under a pressure sufficient to elevate the movable partition, and each pipe being provided with suitable check-valves 12 to prevent back pressure on the tank. The construction of this portion of the mechanism may be similar to that 60 employed for the introduction of an explosive charge to the cylinder of a gas-engine, the explosive mixture being in the form of carbureted air or gas or a fixed gas mixed with any suitable proportion of air.

At a point near the top of the chamber 1 is arranged a pair of electrodes 14, forming the terminals of a sparking-circuit, the circuit being closed in any suitable manner by auxiliary mechanism or by the movement of 75 the partition. The sparking device is situated in a recess at one side of the chamber at such a point that on the upward travel of the partition the latter will be passing the sparking device and the top of its valve-stem will be 80 in operative contact with the top of the chamber to cause an opening movement of the valve.

In operation, the partition and valve being in the position illustrated in Fig. 1, an explosive charge is forced into the chamber below the partition, causing said partition to travel to the top of the chamber, the valve being retained in the closed position by the pressure of the charge. As the partition 90 reaches the point illustrated in Fig. 2 the charge is exploded. The valve being then opened by contact of the stem 8 with the head 2 of the cylinder, the pressure is equalized on both sides of the piston and the latter falls 95 by gravity to the bottom of the chamber, a cushioning effect being produced by a number of small compression-springs 15. When the valve touches the lower head 3, it is closed against the opening 6, and the exploded charge 100

remains at high pressure in that portion of the chamber above the piston. As the engine or other device utilizes this pressure a gradual reduction is effected until the pressure becomes less than that of the explosive mixture in the tank or other source of supply. The check valve or valves then open automatically and raise the partition, gradually forcing the exploded gases out through the pipe 4 until the partition reaches the upper end of the chamber and the fresh charge is exploded.

The construction is such that the fresh charge is kept separate from the exploded gases, a much greater pressure being produced than would be possible if the fresh charge were diluted with the exploded gases.

While the construction herein described, and illustrated in the accompanying drawings, presents the preferred form of generator, it is obvious that various changes in the form, proportions, size, and minor details of the structure may be made without departing from the spirit or sacrificing any of the advantages of our invention.

Having thus described our invention, what we claim is—

1. A pressure-generator comprising a chamber having an inlet for an explosive charge and an outlet for exploded gas, means for exploding the charge, and a valved partition disposed in said chamber and serving to separate the explosive charge from the exploded gas, said partition being movable in one direction by gravity and in the opposite direction by the pressure of an explosive charge.

2. A pressure-generator comprising a chamber having at its lower portion an inlet for an explosive charge and at its upper portion an outlet for exploded gas, means for exploding the charge, and a valved partition arranged in said chamber and movable in one direction

by gravity and in the opposite direction by the pressure of the explosive charge.

3. A pressure-generator comprising a chamber having an inlet for an explosive charge and an outlet for exploded gas, means for exploding the charge, a partition disposed in said chamber and movable in one direction by gravity and in the opposite direction by the pressure of the explosive charge, and a valved passage in said partition for placing in communication the portions of the chamber on opposite sides of said partition.

4. A pressure-generator comprising a chamber having an outlet for exploded gas, a pipe for conveying to said chamber an explosive charge, means for exploding the charge, a movable partition having a port or passage therethrough, and a valve carried by said partition and adapted to be moved to opened and closed positions by contact with the upper and lower heads of the generator.

5. The combination in a pressure-generator, of a cylindrical casing having at one end an inlet for an explosive charge and at the opposite end an outlet for exploded gas, a freely-movable partition disposed in said chamber and serving to separate the fresh charge from the exploded gas, an automatic valve carried by said partition and movable to open and closed positions at opposite ends of the cylinder by contact with the cylinder-heads, and an igniting device in communication with the chamber at a point near the upper end thereof.

In testimony that we claim the foregoing as our own we have hereto affixed our signatures in the presence of two witnesses.

GEORGE EDWARD BLAKE.
CARROLL MELVIN BELL.
